UNITED STATES PATENT OFFICE

165,958

DENTAL HAND-PIECE

Robert B. Black, Corpus Christi, Tex.

Application November 9, 1949, Serial No. 5,958

Term of patent 14 years

(Cl. D24—1)

To all whom it may concern:

Be it known that I, Robert B. Black, a citizen of the United States, residing at Corpus Christi, in the county of Neuces and State of Texas, have invented a new, original, and ornamental Design for Dental Hand-Piece, of which the following is a specification, reference being had to the accompanying drawing, forming a part hereof.

The figure on the drawing is a side elevational view of a dental hand-piece embodying my new design, it being noted that the handle is circular in cross-section throughout its length.

I claim:

The ornamental design for a dental hand-piece, as shown and described.

ROBERT B. BLACK.
